CLAIM

The ornamental design for a tillage tool frame, as shown and described.

DESCRIPTION

FIG. 1 is a side elevational view of the tillage tool frame of the present invention, together with a dashed-line showing of implements attached to the frame and a tractor pulling the frame;

FIG. 2 is an enlarged top plan view of the frame;

FIG. 3 is a side elevational view thereof;

FIG. 4 is a front elevational view thereof;

FIG. 5 is a rear elevational view thereof; and,
FIG. 6 is a perspective view of the tillage tool frame thereof.
